UNITED STATES PATENT OFFICE

2,519,276

GARMENT STRETCHER

Henry L. Needles, West Hartford, and Estelle Parker O'Toole, Wethersfield, Conn.

Application July 16, 1947, Serial No. 761,234

6 Claims. (Cl. 223—61)

1

The present invention relates to new and useful improvements in garment stretchers, and more particularly to an extensible body for insertion in a garment and adjustable to a desired size in accordance with the size of the garment to be stretched, and the invention has for its primary object to provide means for securing the parts of the body in its adjusted position without requiring the use of metal securing means or other metal parts which might have a tendency to rust, or which leave a mark or impression in the garment when stretched thereon.

A further object of the invention is to provide means for easily and quickly adjusting the parts of the device and holding the same in their adjusted position without requiring the use of special tools for that purpose.

A still further object is to provide a device of this character of simple and practical construction, which is neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing the device constructed for use as a stocking stretcher;

Figure 2 is a group perspective view showing the parts of the stretcher separated;

Figure 3 is a fragmentary sectional view taken on a line 3—3 of Figure 1;

Figure 4 is a perspective view of a garment hanger embodying the present invention;

Figure 5 is a group perspective view of the several parts of the garment hanger; and

Figures 6, 7 and 8 are fragmentary sectional views taken respectively on the lines 6—6, 7—7 and 8—8 of Figure 4.

Referring now to the drawings in detail, and first with respect to the form of the invention illustrated in Figures 1 to 3, inclusive, the numeral 5 designates a stocking stretcher generally and which is constructed of a flat plastic body 6 or other suitable non-metallic material, the body including a foot portion 7 and a leg or ankle portion 8 which is inclined upwardly from the upper edge of the foot portion 7.

The foot portion 7 is formed with a pair of longitudinally extending rows of openings 9 which may be of square or rectangular shape

and one surface of the foot portion 7 is formed with a plurality of spaced parallel, longitudinally extending ribs 10.

A foot extension plate 11 is constructed of substantially oval shape and is formed in one surface with a plurality of spaced parallel, longitudinally extending grooves 12 in which the ribs 10 are slidably received.

Also formed on the surface of the extension plate 11 with the grooves 12 are a pair of rows of locking lugs 13 of a shape corresponding to the shape of the openings 9 and adapted for selective insertion therein. Four of the lugs 13 are preferably provided and arranged with two of the lugs in each row, whereas a greater number of the openings 9 are provided so that the extension plate 11 may be adjusted longitudinally at one side of the foot 7 and secured in its adjusted position by inserting the lugs 13 in a corresponding number of the aligned openings 9. The inner edge of each lug 13 is formed with a rearwardly projecting locking tongue 14 which is spaced above the surface of the extension plate 11 to slidably receive an adjacent portion of the foot 7 thereunder, as shown in Figure 3 of the drawing, whereby to lock the foot 7 and extension plate 11 in confronting relation and to hold the extension plate 11 against inward sliding movement with respect to the foot 7.

Accordingly, by inserting the foot 7 and extension plate 11 in a stocking, the stocking will be held in a stretched position and against shrinking while drying on the stocking stretcher.

In Figures 4 to 8, inclusive, the invention is shown constructed for use as a garment hanger which is generally designated at 15 and which includes a pair of confronting plates 16 and 17 shaped in accordance with the construction of a conventional garment hanger.

The opposed face of the plate 16 is provided with a plurality of horizontal ribs 18, while the opposed face of the plate 17 is formed with a corresponding number of grooves 19 in which the ribs 18 are slidably received.

The plate 16 is formed with a double row of horizontal openings 20, while the confronting face of the plate 17 is formed with a double pair of lugs 21 for selective engagement in the openings 20 and provided with the horizontally projecting locking tongues 22 under which an adjacent portion of the face 16 is received to hold the plate against contracting movement.

The upper portion of the plates 16 and 17 are formed with aligned openings 23 and 24, respectively.

A hook 26 is constructed to include upper and lower hook members 27 and 28, the lower hook member 28 being engaged in the slots 23 and 24 to provide a hanger for the plates 16 and 17.

From the foregoing, it will be apparent that the garment hanger 15 may be adjusted horizontally into an extended or retracted position and retained in its adjusted position by the interlocking lugs 21 to thus hold the shoulders of a garment stretched on the garment hanger.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. A garment stretcher comprising an extensible body including a pair of flat confronting sections, interfitting ribs and grooves on the confronting faces of the sections holding the sections in longitudinally aligned position with each other, and means securing the sections to each other in adjusted extended position, said means comprising polygonal interlocking elements.

2. A garment stretcher comprising an extensible body including a pair of flat confronting sections, interfitting ribs and grooves on the confronting faces of the sections holding the sections in longitudinally aligned position with each other, and means securing the sections to each other in adjusted extended position, said means comprising polygonal interlocking elements integrally formed with said sections.

3. A garment stretcher comprising an extensible body including a pair of flat confronting sections, interfitting ribs and grooves on the confronting faces of the sections holding the sections in longitudinally aligned position with each other, and means securing the sections to each other in adjusted extended position, said means comprising polygonal interlocking members integrally carried by one section selectively engaged in openings in the other section.

4. A garment stretcher comprising an extensible body including a pair of flat confronting sections

slidable one against the other, interfitting ribs and grooves on the confronting faces of the sections holding the sections in longitudinally aligned position with each other, one of said sections having a plurality of polygonal shaped openings, and complementary shaped lugs integrally formed with the other of said sections selectively received in said openings.

5. A garment stretcher comprising an extensible body including a pair of flat confronting sections slidable one against the other, interfitting ribs and grooves on the confronting faces of the sections holding the sections in longitudinally aligned position with each other, one of said sections having a plurality of polygonal shaped openings, and complementary shaped lugs integrally formed with the other of said sections selectively received in said openings, said lugs including interlocking tongues holding the sections against contracting movement.

6. A garment stretcher comprising an extensible body including a pair of flat confronting sections slidable one against the other, interfitting ribs and grooves on the confronting faces of the sections holding the sections in longitudinally aligned position with each other, one of said sections having a plurality of polygonal shaped openings, and complementary shaped lugs integrally formed with the other of said sections selectively received in said openings, said lugs including interlocking tongues holding the sections to each other in confronting relation and also holding the sections against contracting movement.

HENRY L. NEEDLES.
